CLAIM

The ornamental design for a toilet plunger and brush kit, as shown and described.

DESCRIPTION

FIG. 1 is a first perspective view of a toilet plunger and brush kit showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is an exploded view of the toilet plunger and brush kit thereof.

The broken lines shown in the drawings depict portions of the toilet plunger and brush kit that form no part of the claimed design.
